AIR SPACE INSULATED ELECTRIC CABLE

Otto Cords, Berlin-Sudende, and Gerhard Nehmiz, Berlin-Grunewald, Germany

Application July 6, 1938, Serial No. 217,794
In Germany July 13, 1937

4 Claims. (Cl. 174—29)

This invention relates to an air space insulating electric cable of the type disclosed in the prior application, Serial Number 175,936, filed November 22, 1937.

The object of the present invention is to provide an air space insulated electric cable, and more particularly a high-frequency cable wherein the support for the central conductor is constituted by at least one tape wound helically about the central conductor in spacial disposal thereto, a thread or threads wound about the said tape and between the convolutions thereof and about the central conductor with a pitch smaller than that of the helically wound tape for the purpose of supporting the central conductor with respect to the helically wound tape, and at least one further tape superimposed on the said first tape and firmly secured thereto for the purpose of securing the position of the supporting thread or threads.

The invention is illustrated by way of example in the accompanying drawing, in which:

Fig. 1 is a perspective view illustrating a supporting system according to the invention.

Fig. 2 is a cross-section showing on enlarged scale a piece of the tape system according to Fig. 1.

Fig. 3 is a modification of Fig. 2, while

Fig. 4 shows an additional embodiment for connecting the layers and securing the thread.

In the drawing 1 is the central conductor of the cable, about which there is disposed in spacial relation thereto a helically wound tape system. In the embodiment shown this tape comprises two superimposed layers 7 and 8. These layers are connected together, for example, by means of an adhesive and may for example, be made of non-metallic material. When the winding is being produced on the machine the supporting thread 4 is wound in such a manner that it is located between the layers 7 and 8 and consequently is securely held in position thereby.

The tape winding, however, is not limited to two layers, and as shown in Fig. 3 there may be provided, for example, three layers 7, 8 and 9. In

this figure the thread 4 is shown as being located between the layers 7 and 8, but naturally it might also be provided between the layers 7 and 9.

In the embodiment according to Figure 4 the two layers 7 and 8, which may consist of paper, are furnished on their oppositely disposed faces with a coating 10 of synthetic resin. As before the thread 4 is disposed between the two layers 7 and 8, and upon the application of heat the synthetic resin 10 is caused to melt, and after hardening it unites the two layers 7 and 8 and thus firmly secures the thread 4.

If desired, the synthetic resin can also be hardened.

We claim:

1. An air space insulated electric cable, and more particularly a high-frequency cable, comprising a central conductor, a support for the said conductor including at least one tape wound helically about the central conductor in spacial disposal thereto, a thread wound about the said tape and between the convolutions thereof and about the central conductor for supporting the central conductor with respect to the helically wound tape, and at least one further tape superimposed on the said first tape and firmly secured thereto for securing the position of the supporting thread.

2. An air space insulated electric cable according to claim 1 in which the helically wound and superimposed tapes consist of paper and are connected together by an adhesive.

3. An air space insulated electric cable according to claim 1 in which the helically wound and superimposed tapes are connected together by synthetic resin which is caused to melt upon the application of heat and unites the tapes when subsequently hardening.

4. An air space insulated electric cable according to claim 1 in which the helically wound and superimposed tapes are connected together by a synthetic resin.
